(57) **CLAIM**

The ornamental design for a beverage can purse as shown and described.

DESCRIPTION

FIG. 1 is a perspective view of a beverage can purse; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; and, FIG. 8 is a perspective view thereof in a state of use holding a beverage container.

Portions of the beverage can purse between the break lines in the drawings form no part of the claimed design. The broken lines are included for the purpose of illustrating environment and portions of the beverage can purse that form no part of the claimed design.

1 Claim, 7 Drawing Sheets
